P. E. WILLIS,

PORTABLE ACETYLENE GENERATOR.
APPLICATION FILED FEB. 20, 1915.

1,197,879.

Patented Sept. 12, 1916.

UNITED STATES PATENT OFFICE.

PRIOR F. WILLIS, OF ST. LOUIS, MISSOURI.

PORTABLE ACETYLENE-GENERATOR.

1,197,879.

Specification of Letters Patent. Patented Sept. 12, 1916.

Application filed February 20, 1915. Serial No. 9,583.

To all whom it may concern:

Be it known that I, PRIOR F. WILLIS, a citizen of the United States, and a resident of the city of St. Louis and State of Missouri, have invented a new and useful Improvement in Portable Acetylene-Generators, of which the following is a specification.

This invention relates to generators for producing acetylene gas from calcium carbide, and is particularly adapted for use with oxy-acetylene flame apparatus, such as is used for cutting and welding metals.

The object of the invention is a portable generator having an automatic carbide feeding mechanism which is operated and controlled by the gas pressure, which is easily started and stopped by hand, which is quickly responsive to small changes in pressure, and which can be adjusted for different pressures.

Further objects of the invention appear hereinafter, and the structural details of the invention are further described in connection with the following description of the generator tank shown in the accompanying drawings.

The invention consists in the flanged joint for attaching the carbide receptacle to the tank, in the double valve arrangement forming the operating part of the carbide measuring device, and in the external arrangement and construction of the adjustable pressure regulator.

35 The invention is particularly defined in the appended claims.

In the drawings, in which like reference characters designate the same parts in the several views, Figure 1 is a central vertical section through a generator embodying the invention, showing the parts in working position; Fig. 2 is a similar view of the lower end of the carbide receptacle, showing the valve operating rod in an intermediate position; Fig. 3 is a top view of the pressure regulator with the cap removed; and Fig. 4 is a top view of the conical shield in the bottom of the carbide receptacle.

The apparatus consists of a portable tank 50 11, having a water inlet and overflow pipe 12 in its side wall at a suitable distance from the bottom, a sludge vent or blow-off valve 13 near the bottom, and a gas pipe outlet connection 14 near the top. The 55 water inlet pipe 12 is provided with a suitable overflow valve and a funnel or other

device for enabling the tank to be filled with water up to the water level 15. The carbide is charged into a receptacle 16, which is suspended within the tank 11 at its top 60 by means of an outturned flange around its upper rim which rests on the outwardly flanged rim of the tank. A head 17, is bolted to the flanged rims of the tank and carbide receptacle and closes the top of the receptacle and tank. The head has a carbide filling hole which is closed by a screw plug 18 during the operation of the generator. The bottom wall of the carbide receptacle 16 is hemispherical, and has a central hole 65 provided with a depending flange 19. A conical valve 20 is seated in the hole in the bottom of the carbide receptacle. The conical valve 20 is slidable on a vertical valve rod 21, and a collar 22 on the valve rod is 70 arranged in a counterbored hole in the under side of the conical valve to engage the under side of the valve and lift it off its seat when the valve rod is raised through more than about one-half of its 75 total vertical movement. The conical valve 20 fits loosely on the valve rod, so that gas may pass by the valve both in open and in closed position into the carbide receptacle 16. The lower end of the valve rod carries 80 a downwardly flaring cone 23.

A loose ring 24 around the flange 19 is freely suspended from the bottom of the carbide receptacle by means of short chains. When the valve operating rod is in its lowest position there is a considerable space between the cone 23 and the lower edge of the ring 24. When the valve operating rod is raised halfway to the top of its movement the cone 23 strikes the lower edge of the 85 loose ring 24, and further upward movement of the rod and cone carries the ring up with them. A shield 25 covers the valve 20 and supports the greater part of the carbide above the bottom of the receptacle, thus preventing 90 the carbide from interfering with the action of the valve. The valve operating rod 21 projects through the head 17. A pipe 26 surrounds the valve operating rod from the shield 25 to the cap 17, and keeps 95 it from contact with the carbide in the receptacle. A tube 27 in line with the pipe 26 projects above the cap 17 and surrounds the valve operating rod nearly to its top end. A regulator cylinder 28 is slidably arranged 100 on the tube 27. The sliding joint between the cylinder and tube is lapped to make it 105 110

fit tight, and as a further precaution, the lower end of the cylinder is bored out to form a recess 29 for oil. The regulator cylinder and recess are kept partly filled with 5 a medium grade machine oil which seals the sliding joint and insures uniformity in the frictional resistance of the parts against movement in response to changes in gas pressure. An elbow 30 is provided for filling 10 the regulator with oil until it overflows the filling opening. The upper end of the elbow is closed by a plug 31. The upper end of the valve rod 21 goes through a hole in a flexible supporting plate 32, and a nut 15 on the end of the valve operating rod sustains it from the plate. The ends of the plate are inserted in notches in the top of the regulator cylinder, and are secured therein by the cap 33. A support 34 which is attached 20 to the head 17 of the tank has a projecting finger 35 over which a link 36 which is attached to the regulator cap 33 can be hooked to hold up the valve rod 21. In the raised position of the valve rod the 25 cone 23 seats against the under side of the flange 19 and precludes the accidental feeding of carbid from the chamber at the lower end of the carbid receptacle into the tank.

To start the operation of the carbid feeding device, the valve rod is dropped by hand to its lowest position, whereupon any carbid in the space within the ring 19 at the lower end of the carbid receptacle will drop into the water in the bottom of the tank and 35 acetylene gas will be evolved. The gas thereby produced will fill the tank and carbid receptacle, and will flow through the pipe 26 into the space within the regulator. If the gas pressure is sufficient to raise the 40 regulator to its highest position the cone 23 on the lower end of the valve rod will engage the ring 24 and under side of the flange 19 and close the bottom opening in the carbid receptacle. At the same time, the 45 valve 20 will be raised clear of its seat and carbid will slide down the sides of the container 16 and fill the space within the ring 24 and flange 19. If the pressure of the gas is insufficient to raise the regulator, the latter 50 must be raised by hand, and then dropped to feed a second charge of carbid into the tank. Hand feeding must be continued until sufficient gas is evolved to raise the regulator to its highest position. The regulator 55 will remain in its highest position until the consumption of the gas has reduced its pressure sufficiently to let the regulator fall, which allows the charge of carbid in the ring 24 and within the flange 19 to fall 60 into the tank, thereby producing more gas and again raising the regulator and valve rod.

The dimensions and arrangement of the flange 19, valve 20, collar 22, cone 23 and ring 24 are such that the cone strikes the

lower edge of the ring and cuts off the further feeding of carbid before or simultaneously with the beginning of the raising of the valve by the collar, as shown in Fig. 2. Further upward movement of the valve 70 rod lifts the ring and valve together until the cone seats against the under edge of the flange. The dimensions of the flange 19 and ring 24 may be varied to suit the charge of carbid to the size of the apparatus and 75 to the closeness of regulation desired. Cast iron rings or scale weights may be piled on top of the regulator to set the apparatus for the desired maximum gas pressure to be maintained. 80

My invention is not restricted to the precise forms and dimensions of the parts shown in the drawings.

I claim the following as my invention:

1. A generator comprising a pressure 85 tank, a carbid receptacle arranged in the upper part of the tank and having a carbid discharge opening in its bottom surrounded by a depending flange, and means for regulating the feeding of carbid through said discharge opening comprising a valve seated over said opening, a valve rod extending through said opening and slidably engaging said valve, said valve rod having an enlargement at its lower end adapted to engage said 90 flange and close said opening in raised position of said rod, a loose ring surrounding said flange and freely suspended below it and above said enlargement, means on said valve rod adapted to engage and lift said 95 valve off its seat in raised position of said rod, said enlargement engaging said ring to close the bottom of said discharge opening prior to the lifting of said valve by said rod, and means operated by excessive gas 100 pressure to raise said rod and hold it in raised position until the gas pressure falls below normal. 105

2. A generator comprising a pressure tank, a carbid receptacle, and means for controlling the feeding of fuel from said receptacle into said tank, said controlling means comprising a valve rod extending out of said tank, a tube projecting from the top of said tank, said tube inclosing said 110 valve rod and communicating with said tank, and a fluid pressure regulator slidably mounted on said tube and connected to said valve rod, said regulator consisting of a sleeve encircling the end of said tube and 115 slideable thereon, a packing between said sleeve and said tube, and a removable closure for the end of said sleeve inclosing the open end of said tube. 120

3. A generator comprising a pressure 125 tank, a carbid receptacle, and means for controlling the feeding of carbid from said receptacle into said tank, said controlling means comprising a valve rod extending out of said tank, a tube projecting from said 130

5 tank, said tube inclosing said valve rod and communicating with said tank, and a fluid pressure regulator slidably mounted on said tube and having a yieldable connection with
10 5 said valve rod, said regulator consisting of a sleeve encircling the end of said tube and slidably thereon, a packing between said sleeve and said tube, and a cap closing the open end of said tube, and a thin metal plate secured to said regulator beneath said cap and supporting the outer end of said valve rod.

4. A generator comprising a carbide receptacle having a carbide discharge opening in its bottom surrounded by a depending flange, a valve rod extending through said opening and having its upper end projecting out of said generator, said valve rod 20 having an enlargement at its lower end

adapted to engage said flange and close said opening in raised position of said rod, a loose ring surrounding said flange and freely suspended below it and above said enlargement, said enlargement engaging 25 said ring to close the bottom of said discharge opening prior to engaging said flange, means operated by excessive gas pressure to raise said rod and hold it in raised position until the gas pressure falls 30 below normal, and means for engaging said valve rod and holding it in raised position against said opening.

Signed at St. Louis, Mo., this 17th day of February, 1915.

PRIOR F. WILLIS.

In the presence of—
AMASA M. HOLCOMBE,
EDGAR T. FARMER.
